UNITED STATES PATENT OFFICE.

CHARLES LA DOW, OF ALBANY, NEW YORK.

SULKY SPRING-TOOTH HARROW AND CULTIVATOR.

SPECIFICATION forming part of Letters Patent No. 269,068, dated December 12, 1882.

Application filed February 11, 1882. (No model.)

To all whom it may concern:

Be it known that I, CHARLES LA DOW, a citizen of the United States, and residing in the city and county of Albany, and State of New York, have invented a new and useful Improvement in Sulky Spring-Tooth Harrows and Cultivators, of which the following is a specification.

This improvement relates to that class of cultivators which employ vibratory spring-teeth to work the soil, and are mounted on wheels and capable of being adjusted and set to work the soil to any required depth.

This invention consists in the combination of a draft-frame, a rocking bar connected therewith, ground-wheels supporting the bar and serving as bearings for the rocking movement of the same, a series of spring-teeth of different lengths, adjustable in a direction around the rocking bar relatively to each other to vary the penetration of their points, and having their points arranged in different vertical planes across the line of draft, and means for rocking the bar and teeth.

The invention further consists in the combination of a draft-frame, a rocking bar connected therewith, ground-wheels supporting the bar and serving as center bearings for the rocking movements of the same, spring-teeth attached in series to the rocking bar with their points arranged in different vertical planes, and means whereby the teeth may be varied and held in one series relatively to the teeth in another series by frictional contact between the teeth and their carrying rocking bar.

The invention further consists in the combination of a draft-frame supported by wheels, a rocking bar attached to the frame and arranged between the wheels, a series of teeth on the bar, and a section or extension also carrying teeth, and capable of being attached to the rocking bar for varying the width of the soil-working parts of the machine.

The invention further consists in the combination of a draft-frame, a rocking bar attached thereto, mechanism for rocking the bar and holding it as adjusted, teeth adjustably attached to the bar, and mechanism whereby part of the teeth can be reversed without interfering with the rocking of the bar and the work and movement of the other teeth.

The invention further consists in the com-

bination of a draft-frame, a rocking bar, ground-wheels arranged on the bar, and in the hubs of which wheels the bar rocks, and vibrating spring-teeth mounted on said bar, the teeth adjacent to the wheel-hubs being extended or bent laterally to admit the hubs between them, and thereby maintain the proper relative position of the cutting points of all the teeth.

Referring to the drawings, Figure 1 represents a top view of my invention. Fig. 2 represents a side view of the same. Fig. 3 represents the adjustable section or extension for varying the width of the operation of the machine.

A A are the ground-wheels, and are mounted on the axle C'. B is the cross-bar; D, the pole; O O, the braces securing the pole and cross-bar together. E is the toothed rack fastened to the cross-bar. The axle C' is preferably made of gas-pipe or other hollow tubing, and is arranged to rock through the center of the wheel-hubs, which act as journal-bearings therefor. The cross-bar is connected with the axle by eye-bearings H I H I. The teeth a a are preferably made of flat spring-steel, and are bent at their upper ends to form a loop or clasp, partially encircling the axle C'. The teeth are made of different lengths and curvatures, so as to bring their points in different vertical planes across the line of draft, in order to thoroughly work the ground at one transit of the machine, and yet allow stones and rubbish to readily pass through between the teeth.

b b' are clips arranged above and below the clasp of the tooth.

c c are clamping-bolts for locking the tooth to the axle by frictional contact.

F is a ratchet-lever engaging with the rack E by means of suitable spring and pawl. By rocking the lever the teeth can be either forced into the ground, or raised above it, the rack and pawl holding the teeth and their axle-bar in any position adjusted or desired.

In order to force all the teeth into the earth uniformly at different depths of penetration, the clamping-bolts c c may be loosened on the rear series of teeth, and they can be set at the same depth as the front teeth, the bolts retightened, and the teeth securely held in any desired position relatively to their axle-bar.

The upper end of the tooth-clasp has an upward or return bend to prevent the binding-clips from slipping off.

When it is desired to use the machine as a 5 cultivator of rowed crops the bolts and clips on the teeth near the center of the machine may be loosened sufficiently to allow the axle-bar to be rocked freely within the clasps of said teeth. These center teeth may then be 10 thrown forward until their weight will cause them to overbalance, and they can be thus carried in reversed position on the cross-bar without being disturbed by the rocking of the axle when operating the teeth at work, and 15 without being seriously in the way of the driver on his seat.

O is a section or extension of the axle C'. Q is a metal pin, which enters the bore of the axle-extension C, and is securely held thereto 20 by pins p p. When it is desired to increase the width of the operation of the machine the linchpin p' is withdrawn from the axle C' and that portion of the pin Q which projects beyond the shoulder of the axle-extension C is 25 thrust into the bore of the axle C', and the linchpin p' is again inserted in its original place and passes through the pin Q, securely retaining said pin Q and the axle-extension C relatively to the axle C', the linchpin performing 30 the office of keeping both the wheel and the axle-extension in place.

Spring-teeth are placed upon the axle-extension in the same manner as upon the axle between the wheels. When cultivating rowed 35 crops or on any other proper occasion the axle-extensions may be dispensed with and the machine used without them. The teeth adjacent to the wheels are bent sidewise in order to bring their cutting-points in proper place relative to their line of draft and to the cut of their 40 adjoining teeth, and at the same time allow a hub of suitable length to be used on the axle between the teeth in proportion to the height of the wheel. The seat S and standard V are 45 mounted in the socket on draft-pole D in the usual manner. The draft-pole D and cross-bar B are kept from undue lateral movement by placing the eye-bearings H I H I between the tooth-clasps on the axle C'. Any of the 50 teeth between the wheels may be loosened on the axle and thrown forward and reversed on the cross-bar without affecting the work and rocking movements of such teeth as may be left working the soil.

55 The machine may be made either with or without extensions for the axle and of any width desired, and the extensions may be used on one side only or on both. The teeth may

be constructed so that their points will stand in one vertical plane or several across the line 60 of draft. Wheels of any diameter may be used, according to the nature of the work required.

Having described my invention, what I claim, and desire to secure by Letters Patent, is—

1. The combination of a draft-frame, a rocking bar connected therewith, ground-wheels supporting the bar and serving as bearings for the rocking movement of the same, a series of spring-teeth of different lengths, adjustable in a direction around the rocking bar relatively to 70 each other to vary the penetration of their points, and having their points arranged in different vertical planes across the line of draft, and means for rocking the bar and teeth, substantially as described. 75

2. The combination of a draft-frame, a rocking bar connected therewith, ground-wheels supporting the bar and serving as center bearings for the rocking movements of the same, spring-teeth attached in series to the rocking bar with their points arranged in different vertical planes, and means whereby the teeth may be varied and held in one series relatively to the teeth in another series by frictional contact between the teeth and their carrying rock- 80 ing bar, substantially as described. 85

3. The combination of a draft-frame supported by wheels, a rocking bar attached to the frame and arranged between the wheels, a series of teeth on the bar, and a section or extension also carrying teeth and capable of being attached to the rocking bar for varying the width of the soil-working parts of the machine, substantially as described. 90

4. The combination of a draft-frame, a rocking bar attached thereto, mechanism for rocking the bar and holding it as adjusted, teeth adjustably attached to the bar, and mechanism whereby part of the teeth can be reversed without interfering with the rocking of the bar and the work and movement of the other teeth, substantially as described. 95

5. The combination of a draft-frame supporting a rocking bar, ground-wheels arranged on the bar, and in the hubs of which wheels 100 the bar rocks, and vibratory spring-teeth mounted on said bar, the teeth adjacent to the wheel-hubs being extended or bent laterally to admit the hubs between them and thereby maintain the proper relative position of the 105 cutting-points of all the teeth, substantially as described.

CHARLES LA DOW.
